US0D1002654S

(12) **United States Design Patent** (10) **Patent No.:** **US D1,002,654 S**
(45) **Date of Patent:** **** Oct. 24, 2023**

(54) **DISPLAY SCREEN OR PORTION THEREOF
WITH GRAPHICAL USER INTERFACE**

(71) Applicant: **McMaster-Carr Supply Company**, Elmhurst, IL (US)

(72) Inventors: **Javier Calvo Mendoza**, Chicago, IL (US); **Sheena Wang**, Chicago, IL (US); **Mira Staykova**, Elmhurst, IL (US)

(73) Assignee: **MCMASTER-CARR SUPPLY
COMPANY**, Elmhurst, IL (US)

(**) Term: **15 Years**

(21) Appl. No.: **29/813,283**

(22) Filed: **Oct. 27, 2021**

(51) LOC (14) Cl. **14-04**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing a first image of the claimed design.

The outermost broken lines in the FIGURE show a display screen or portion thereof, and form no part of the claimed design. The other broken lines in the FIGURE show portions of the graphical user interface that form no part of the claimed design.

MERV Filter Rating Edit Close

The MERV system is an industry standard that rates air filters on a scale from 1 to 16 based on how well they remove particles in three size ranges. A higher rating means a filter removes more particles.

Removes fewer particles

Prefilter

Protect HVAC equipment and extend the life of other higher-efficiency filters. Prefilters capture large particles such as soot, dust, textile fibers, and mold spores.

MERV 4

Unfiltered Air Filtered Air

MERV 4 filters remove fewer than 20% of large particles (3 to 10 microns), such as mold spores and cement dust.
